UNITED STATES PATENT OFFICE.

EMIL EINFELDT, OF DAVENPORT, IOWA, ASSIGNOR TO BETTENDORF METAL WHEEL COMPANY, A CORPORATION OF ILLINOIS.

METHOD OF MAKING METAL WHEELS.

SPECIFICATION forming part of Letters Patent No. 700,024, dated May 13, 1902.

Application filed August 10, 1901. Serial No. 71,581. (No model.)

To all whom it may concern:

Be it known that I, EMIL EINFELDT, of Davenport, county of Scott, and State of Iowa, have invented a new and useful Improvement 5 in Methods of Making Metal Wheels, of which the following is a specification.

In connecting the members of metal wheels—that is, the hub, rim, and spokes—it is the practice under certain methods of 10 procedure to form either at the inner side of the rim or outer side of the hub, or at both places, a shoulder by upsetting the spoke at these points by an endwise pressure thereon. The result of this action is the formation of 15 a shoulder and a shortening of the spoke, and inasmuch as the diameter of the spokes often varies and their structural formation is not in every case uniform the shortening is greater in some cases than in others, which 20 results in an unequal strain on the spokes and rim and in many cases in an unevenness in the rim. This variation in the length of the spokes is particularly noticeable and objectionable where the spoke is connected with 25 both the rim and hub by the formation of heads on the ends of the spoke on the inside of the hub and outside of the rim simultaneously with the formation of the shoulders between the hub and rim.

30 The aim of my invention is to overcome these objections resulting from the shortening of the spokes; and it consists of the method of manufacture by which the material of the spoke, either at the inner side of 35 the rim or the outer side of the hub, or at both places, is forced or jammed up against the adjacent members of the wheel to form a shoulder without in any manner changing the length of the spoke between the rim and 40 the hub. In this way the tension of each spoke and its strain on the hub and rim will be uniform.

The forcing up of the material against the adjacent member of the wheel may be effected in a number of ways. For instance, the outer material of the spoke may be scraped up against the hub or rim in the form of a shoulder, or an annular shoulder or flange may be previously formed on the spoke and 45 bent or jammed into forcible engagement

with the rim or hub. In each case the metal of the spoke is forced in the form of a shoulder firmly against the adjacent member of the wheel without disturbing the interior of the spoke or changing its length between the 55 rim and the hub, and the shoulder thus formed serves, in connection with the head on the end of the spoke, to securely fasten the latter in place. I propose to utilize this peculiar method, among other purposes, for the 60 formation of a wheel in which the spokes will be under a tension, which is accomplished by heating one or both ends of the spoke before or at the time it is secured in place, so that the contraction from cooling will place the 65 spoke under tension.

Referring to the drawings, Figure 1 is a view of the rim, spoke, and hub before assembled and in the form for carrying out my method in the preferred manner. Fig. 2 is a 70 view of the hub, spoke, and rim assembled ready to be acted on under my method. Fig. 3 is a view of the completed wheel. Fig. 4 is a view showing how my method may be practiced to produce a wheel of a different 75 form.

In the accompanying drawings, in carrying out my method in the preferred manner I provide a closed rim 1, formed at intervals with holes 2 to receive tenons 3 on the outer 80 ends of spokes 4, which spokes have adjacent to the tenon a shoulder 5 and at its opposite end a thickened or enlarged portion 6, which is adapted to be inserted through an opening 7 in a hub 8. In assembling these 85 parts or members of the wheel preparatory to securing them in fixed relation by my method the hub and rim are held in the relations they will occupy in the completed wheel, and the enlarged end of the spoke is 90 passed through an opening in the hub and the spoke pushed endwise toward the center of the hub until its tenon clears the inner edge of the rim, after which the tenon is brought opposite the hole in the rim and the 95 spoke pushed outward until the shoulder 5 thereon abuts against the rim, as shown in Fig. 2. By suitable means the outer ends of the spoke at the inside of the hub and the outside of the rim are headed, preferably, by up- 100

setting these ends, and at the same time by suitable means the shoulder 5 on the spoke at the inner side of the rim is jammed firmly up against the rim, and the thickened portion 6 of the spoke is scraped or forced up against the hub at the outer side, as shown in Fig. 3. The effect of this operation is to produce heads or shoulders 9 at the ends of the spokes and a shoulder 10 at the outer side 10 of the hub, which shoulders will fasten the spoke securely to the rim and hub, and this without changing the length of the spoke between the rim and hub. After this operation is finished a second spoke is set in 15 place and acted on as before to secure it to the rim and hub, and these operations are repeated until all the spokes are in place and the wheel is completed.

I prefer to upset the outer ends of the spokes 20 by heading-tools 11 and 12 and to jam up the shoulder 5 and scrape up the thickened portion of the spoke by coöperating dies 13, which dies and heading-tools are adapted to act in unison, the die at the hub end of the 25 spoke and heading-tool there acting toward each other to perform their functions at the same time that the die at the opposite end of the spoke and the heading-tool there are brought together to perform their functions; 30 but it will be understood that the invention is not limited to this particular mechanism, as any means may be employed, provided the metal of the spoke between the hub and rim is forced up against the adjacent member of 35 the wheel without decreasing or varying the length of the spoke between the hub and rim.

While it is preferred that the spoke be thickened where the shoulder is scraped up so as not to weaken it by reducing its diameter, 40 this is not absolutely essential, for the diameter of the spoke may be the same throughout its length. Further, instead of scraping up a portion of the spoke, as described, the latter may be previously provided at the 45 hub end with a shoulder similar to that at the rim end, and these shoulders jammed up against the hub. This action would secure a firm engagement of the spoke with the hub without shortening the former; but 50 it would be necessary in order to set the spoke in place with this previously-formed shoulder either to omit the shoulder at the rim end and scrape up a shoulder at that point or leave the ends of the rim disconnect- 55 ed until all the spokes are secured in place. Further, the shoulders may be formed at both the inner side of the rim and outer side of the hub by scraping up the material of the spoke. In all these different ways of securing the 60 spoke there is no change in its length between the rim and the hub, the action being to act on the exterior of the metal of the spoke without disturbing its interior between the rim and hub, and this is the essence of 65 the invention.

While the spokes may be acted on in the manner described in a cold state, I propose

in certain cases where it is desired to place the spoke under tension and produce a "tension-wheel" to heat one or both ends of the 70 spoke either just before or at the time they are fastened in place, the result being that when they cool they will contract slightly, but uniformly, which will place them under a uniform tension. By reason of the fact that 75 the fastening of the spoke does not change its length the tension is due wholly to contraction by cooling, and this being uniform and the same in all the spokes and not modified by any slight changes in diameter or structure of the spokes the pull on the spokes will be the same and the circular form of the rim 80 preserved.

In Fig. 4 I have illustrated a wheel in which the spoke on its inner end has a head previously formed, which is engaged with the inner side of the hub by passing the spoke through an open slot 14 in the end of the hub. At its outer end the spoke has a shoulder 15 formed on it by scraping up the material of 90 the spoke at the inner side of the rim, a head 16 being formed on its extreme outer end at the outer side of the rim, which, in connection with the scraped-up shoulder, firmly secures the spoke to the rim. My method, it 95 will be understood, is applicable as well to the formation of a wheel of this character, inasmuch as it comprehends the forcing up of the metal of the spoke between the hub and rim into engagement with the adjacent 100 member of the wheel (the rim) without changing the length of the spoke between the rim and hub. If the end of the spoke is heated, its cooling will, as in the case just described, contract the spoke and place the same under 105 tension.

Having thus described my invention, what I claim is—

1. In the method of making metal wheels, fastening a spoke simultaneously to both the 110 hub and the rim by forcing the outer material of the spoke in the form of an integral shoulder into engagement with the adjacent member of the wheel without disturbing the interior of the spoke. 115

2. In the method of making metal wheels, forcing the outer material of the spoke into engagement with the adjacent member of the wheel without disturbing the interior of the 120 spoke.

3. In the method of making metal wheels, scraping up the external material of the spoke in the form of a shoulder into forcible engagement with the adjacent member of the wheel without disturbing the interior of the 125 spoke.

4. In the method of making metal wheels, scraping up the external material of the spoke into forcible engagement with the outer side of the hub without disturbing the interior of the 130 spoke.

5. In the method of making metal wheels, forcing the external material of the spoke against both the inner side of the rim and

the outer side of the hub without changing the length of the spoke between the rim and hub.

6. In the method of making metal wheels, upsetting the end of the spoke and simultaneously forcing up the material of the spoke against the adjacent member of the wheel without changing the length of the spoke between the rim and hub.

10 7. The method of making metal wheels, which consists in assembling in proper relations the hub, rim and spoke and simultaneously upsetting the outer ends of the spoke and forcing the material of the spoke against 15 the inner side of the rim and outer side of the hub without changing the length of the spoke between the rim and hub.

8. In the method of making metal wheels, providing a hub, rim and a spoke with a 20 thickened or enlarged portion, and scraping up this thickened portion of the spoke into forcible engagement with the adjacent member of the wheel without disturbing the interior of the spoke or changing its length between the rim and hub.

25 9. In the method of making metal wheels, providing a hub, rim and a spoke with a thickened portion and an external shoulder, scraping up the thickened portion, and jamming 30 up the shoulder into engagement with the hub and rim respectively without reducing

the length of the spoke between the rim and hub.

10. The method of making metal wheels which consists in providing a rim having holes, 35 a hub having holes, and a spoke having a thickened portion and a shoulder, passing the thickened end of the spoke through a hole in the hub, and the opposite end of the spoke through a hole in the rim, upsetting the outer 40 ends of the spoke against the outer side of the rim and the inner side of the hub respectively, jamming up the shoulder on the spoke at the inner side of the rim, and scraping up the outer material of the spoke against the 45 outer side of the hub in the form of a shoulder.

11. In the method of making metal wheels, providing a closed rim, a hub and a spoke, heating the end of the spoke and securing the same to the hub and rim while heated, by 50 forcing the outer material of the spoke in the form of a shoulder into engagement with the adjacent member of the wheel without disturbing the interior of the spoke.

In testimony whereof I hereunto set my hand, this 8th day of July, 1901, in the presence of two attesting witnesses.

EMIL EINFELDT.
